CLAIM

The ornamental design for a computer display panel with graphical user interface comprising a set of images for fashion ensemble planning, as shown and described.

DESCRIPTION

FIG. 1 is a front view of a computer display panel with graphical user interface comprising a set of images for fashion ensemble planning showing a first image of the set; FIG. 2 is a front view thereof showing a second image of the set; FIG. 3 is a front view thereof showing a third image of the set; FIG. 4 is a front view thereof showing a fourth image of the set; FIG. 5 is a front view thereof showing a fifth image of the set; FIG. 6 is a front view thereof showing a sixth image of the set; FIG. 7 is a front view thereof showing a seventh image of the set; FIG. 8 is a front view thereof showing an eighth image of the set; FIG. 9 is a front view thereof showing a ninth image of the set; FIG. 10 is a front view thereof showing a tenth image of the set; FIG. 11 is a front view thereof showing an eleventh image of the set; FIG. 12 is a front view thereof showing a twelfth image of the set; FIG. 13 is a front view thereof showing a thirteenth image of the set; FIG. 14 is a front view thereof showing a fourteenth image of the set;

FIG. 15 is a front view thereof showing a fifteenth image of the set; FIG. 16 is a front view thereof showing a sixteenth image of the set; FIG. 17 is a front view thereof showing a seventeenth image of the set; FIG. 18 is a front view thereof showing an eighteenth image of the set; FIG. 19 is a front view thereof showing a nineteenth image of the set; FIG. 20 is a front view thereof showing a twentieth image of the set; FIG. 21 is a front view thereof showing a twenty-first image of the set; FIG. 22 is a front view thereof showing a twenty-second image of the set; FIG. 23 is a front view thereof showing a twenty-third image of the set; FIG. 24 is a front view thereof showing a twenty-fourth image of the set; FIG. 25 is a front view thereof showing a twenty-fifth image of the set; FIG. 26 is a front view thereof showing a twenty-sixth image of the set; FIG. 27 is a front view thereof showing a twenty-seventh image of the set; FIG. 28 is a front view thereof showing a twenty-eighth image of the set; FIG. 29 is a front view thereof showing a twenty-ninth image of the set; FIG. 30 is a front view thereof showing a thirtieth image of the set; FIG. 31 is a front view thereof showing a thirty-first image of the set; FIG. 32 is a front view thereof showing a thirty-second image of the set; FIG. 33 is a front view thereof showing a thirty-third image of the set; FIG. 34 is a front view thereof showing a thirty-fourth image of the set; FIG. 35 is a front view thereof showing a thirty-fifth image of the set; FIG. 36 is a front view thereof showing a thirty-sixth image of the set; FIG. 37 is a front view thereof showing a thirty-seventh image of the set; FIG. 38 is a front view thereof showing a thirty-eighth image of the set; FIG. 39 is a front view thereof showing a thirty-ninth image of the set; FIG. 40 is a front view thereof showing a fortieth image of the set; FIG. 41 is a front view thereof showing a forty-first image of the set; FIG. 42 is a front view thereof showing a forty-second image of the set; FIG. 43 is a front view thereof showing a forty-third image of the set; FIG. 44 is a front view thereof showing a forty-fourth image of the set; FIG. 45 is a front view thereof showing a forty-fifth image of the set; FIG. 46 is a front view thereof showing a forty-sixth image of the set;

FIG. 47 is a front view thereof showing a forty-seventh image of the set;

FIG. 48 is a front view thereof showing a forty-eighth image of the set;

FIG. 49 is a front view thereof showing a forty-ninth image of the set;

FIG. 50 is a front view thereof showing a fiftieth image of the set;

FIG. 51 is a front view thereof showing a fifty-first image of the set;

FIG. 52 is a front view thereof showing a fifty-second image of the set;

FIG. 53 is a front view thereof showing a fifty-third image of the set;

FIG. 54 is a front view thereof showing a fifty-fourth image of the set;

FIG. 55 is a front view thereof showing a fifty-fifth image of the set;

FIG. 56 is a front view thereof showing a fifty-sixth image of the set;

FIG. 57 is a front view thereof showing a fifty-seventh image of the set;

FIG. 58 is a front view thereof showing a fifty-eighth image of the set;

FIG. 59 is a front view thereof showing a fifty-ninth image of the set; and,

FIG. 60 is a front view thereof showing a sixtieth image of the set.

The broken lines in the drawings illustrate a computer display panel and form no part of the claimed design.

The claimed design is directed to the collective appearance of the set of images of the graphical user interface.
